UNITED STATES PATENT OFFICE.

WILLIAM N. RICHARDS, OF LYONS, NEW YORK.

CAR-COUPING.

SPECIFICATION forming part of Letters Patent No. 272,979, dated February 27, 1883.

Application filed January 15, 1883. (No model.)

To all whom it may concern:

Be it known that I, WILLIAM N. RICHARDS, of Lyons, Wayne county, New York, have invented a certain new and useful Improvement 5 in Car-Couplings; and I do hereby declare that the following is a full, clear, and exact description of the same, reference being had to the accompanying drawings, in which—

Figure 1 is an elevation, partially in section of my improved coupling. Fig. 2 is a plan of the slide for operating the weighted lever that holds the coupling-link. Fig. 3 is a side elevation of the upper end of the lever enlarged. Fig. 4 is a section showing 10 the curved seat in the draw-bar, on which the head of the lever rides. Fig. 5 is a front view of the head of the lever and the curved seat on which it rides. Fig. 6 is a cross-section of the draw-bar and a front elevation of a car, 15 showing the crank-rod for operating the slide that connects with the lever. Fig. 7 is a section through the ball of the weighted lever. Fig. 8 is a modification of the slide for operating the lever.

20 My improvement relates to car-couplings in which a weighted lever or arm is used which holds the coupling link or shackle.

The invention consists in the peculiar construction of the draw-bar by which the coupling-link can be held at any desired elevation to be coupled to cars of varying heights; in the peculiar construction of the weighted lever by which the link can be raised at any desired position, and in the combination, with the 30 weighted lever, of a slide by which the lever is thrown forward to disengage the link, or to raise it, and a crank-rod connected with the slide by which the latter is operated, all as hereinafter described.

35 In the drawings, A A indicate the draw-bars, and B the coupling link or shackle. The usual open flaring mouth, a, is made in the front end of the draw-bar, and in the rear of this is another flaring cavity, b, beveled reversely to the outer mouth, as shown in the sectional view, Fig. 1. Between these two cavities is a contracted throat, c, of just such size as will allow the link to pass freely and work easily.

40 C is the coupling-lever, having a weight, d, of any desired kind at its lower end, which tends to hold the lever vertically. The link in entering the draw-head strikes the upper

end of the lever, deflects it, and passes behind it to its proper position, and is instantly and securely locked by the automatic action of the 55 weight, or the weight and spring combined. The upper end of the lever strikes a stop, f, which forms a solid bearing and takes the strain when the coupling is under tension. The upper end of the lever is provided with a 60 hook, g, on its back side, for a purpose presently to be described. The lower end of the lever enters a slot in the weight d and is secured in place by means of a removable pin, h, so that if the lever becomes broken at any time it can 65 be removed and replaced by another without much trouble. This is done by passing it through a slot, w, in the top of the draw-bar, said slot being covered by a slide, v.

The lever has no pivot, but has an enlarged 70 head with two curved shoulders, i i, on the sides which rest and ride up on corresponding curved seats, k k, in the draw-head, by which means the lever is held in place and is prevented from dropping out, and also has freedom of action 75 in turning for the purposes of coupling and uncoupling.

D is a slide on the under side of the draw-bar, resting in bearings or boxes l l and having a free longitudinal movement. At the 80 front end it has a slotted head, m, which receives the lever, and at the rear end it has a loop or stirrup, n, which receives the cranked rod hereinafter described.

The slotted head m may either have the slot 85 inclosed, as shown in Fig. 2, or open at the outer end, as shown in Fig. 8, the action of the slide in throwing the lever forward being the same in both cases. The object of the closed form shown in Fig. 2 is to lock the lever in place and prevent it from swinging 90 when the coupling is engaged.

E is a cranked rod, resting and turning in bearings p p under the end of the car G. At the ends of the rod, and near the sides of the 95 car, are handles r r, by which the rod is operated without going between the cars, and in the center is a crank, s, which embraces the draw-bar and rests at its lower end in the stirrup n in the slide D.

100 The operation is as follows: By throwing the cranked rod forward the slide is thrown forward with it, swinging the weighted lever also forward from the vertical position shown

in full lines to the inclined position shown in dotted lines, Fig. 1, and enabling the coupling to be uncoupled when there is sufficient slack between the cars, and when the link is thrown 5 fully back. The same forward movement of the parts enables the link to be raised to an inclined position to couple with a higher car, the hook of the lever catching the link in that case and raising the outer end of the link to 10 any desired height from its lowest position, according to the extent to which the lever is thrown by the cranked rod and the slide. By this means the operator holding the handle of the cranked rod has perfect control of the link, 15 and can guide the same to the couplings of other cars of any height without going between the cars or incurring any risk whatever, thus making the coupling automatic and avoiding all dangers that arise from going between 20 the cars. In this connection the two reverse-flaring cavities *a b* in the draw-head are essential to allow the link to stand either at a downward or an upward incline, as indicated by the dotted lines, Fig. 1, the rear cavity allowing the inner end of the link to play up and 25 down, while the outer cavity allows the same

movement to the outer end of the link resting in the throat *c* as a fulcrum.

In case the open slotted form of the head of the slide is used, as in Fig. 8, a spring, *u*, may 30 be attached to the weighted lever, connecting back to the draw-head; but this spring may be dispensed with, if desired.

j is a hole for the use of the ordinary coupling-pin.

Having thus described my invention, what I claim as new is—

In a car-coupling, the combination of the draw-head provided with the reverse-flaring cavities *a b* and the shoulders *k k*, the weighted 40 lever *C*, provided with the hook *g* and shoulders *i i*, the slide *D*, provided with the slotted head *m* and stirrup *n*, and the cranked rod *E*, engaging with the slide, as shown and described, and for the purpose specified. 45

In witness whereof I have hereunto signed my name in the presence of two subscribing witnesses.

WM. N. RICHARDS.
